[57] CLAIM

The ornamental design for a compact, as shown and described.

DESCRIPTION

FIG. 1 is a top plan view of a compact showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a bottom plan view thereof; and

FIG. 7 is a perspective view in the open condition of FIG. 1 (which does not include the tassel) of a second embodiment of my design wherein the only difference is the inclusion of the tassel.
